DEVICE FOR USE IN THE MANUFACTURE
OF ORNAMENTAL FABRICS

Alfred Tiesler, Wittenberge, near Potsdam, Germany, assignor to The Singer Manufacturing Company, Elizabeth, N. J., a corporation of New Jersey

Application May 16, 1933, Serial No. 671,328
In Germany May 20, 1932

30 Claims. (Cl. 112—9)

This invention relates to devices for use in the manufacture of ornamental fabrics, particularly pile fabrics, fringed fabrics and the like, to be used for instance, as coverings, such as floor coverings, cushion covers, and the like.

It is already known to wind yarn or like material around a flat bar in manner to form loops enchain'd along one edge of said bar, whereupon the chain is secured to a base fabric or backing by stitching along said edge, and the bar is then withdrawn from the loops which are cut to form tufts.

It is also known to wind yarn or like material in loops around a forked member or bar, and to secure the wound yarn to a base fabric or backing by means of a line or lines of stitches formed in the gap between the prongs of the fork, whereupon the loops may be cut to form tufts.

The device of my invention may equally be used in the performance of both these known methods.

As hereinafter described, my said device comprises a main or primary bar fitted with a loop-cutting knife and a knife guard, and an auxiliary bar secured to said main bar so as to be removable and widthwise adjustable relatively to the main bar.

The invention is illustrated in the accompanying drawings in which Fig. 1 is a plan view, Fig. 2 a fragmentary side elevation, and Fig. 3 a section on the line *a—a* of Fig 1, showing a first embodiment; Figs. 4—13 show a modification incorporating two knives having cutting edges at an acute angle to one another, Fig. 4 being a plan view, Fig. 5 an inverted plan view, and Fig. 6 a fragmentary side elevation. Figs. 7, 7*a* and 7*b* are, respectively, plan, end and side views of the knife assembly. Figs. 8 and 8*a* are, respectively, plan and end views of a backing plate element of the knife assembly. Figs. 9 and 9*a* are, respectively, plan and end views of one of the knife elements of the knife assembly. Figs. 10 and 10*a* are, respectively, plan and end views of another knife element of the knife assembly. Fig. 11 is a fragmentary plan view showing the knife seat on the main bar of the device. Fig. 12 is a side view of the parts shown in Fig. 11, and Figs. 13 and 13*a* are, respectively, edge and face views of the adjustable bar-spacing clip. Figs. 14 and 15 are plan views showing a further modification, while Figs. 16 and 17 are plan views showing yet another modification.

The device illustrated in Figs. 1—3 inclusive comprises a thin flat bar or straight-edge 1 of spring metal to the upper face of which a knife

2 is removably secured by screws 3, said knife 2 having its cutting edge inclined to and extending beyond one of the parallel edges of the bar 1.

Secured to the under face of the bar 1 as by screws or rivets 4 is the shank 5 of a guard element made of thin sheet metal and having a U-shaped guard portion 6 joined to said shank 5, said guard portion 6 embracing the cutting edge of the knife 2 and being spaced therefrom to permit the passage of yarn between said cutting edge 65 and the guard 6.

Upstanding from the bar 1 near its proximal end is a screw-threaded pin 7 engaged by a pinching nut 8 and penetrating a slot 9 in the cranked end 10 of an auxiliary bar 11 adjustable widthwise of the bar 1. The bars 1, 11 thus constitute the prongs of a fork. The slot 9 is entered also by a stop pin 12 upstanding from the bar 1 adjacent to the pin 7. In Fig. 1 the stitch-receiving gap between the bars 1, 11 is shown 75 as being about equal to the width of the auxiliary bar 11, it being understood that the width of the gap between the bars 1, 11 may be varied by virtue of the pin and slot connection 7, 9 80 for the purpose of producing pile fabrics of different heights of pile.

13 denotes a spacing member adapted to be fitted over the free ends of the bars 1, 11, such spacing member being constructed in manner similar to that of the combined guard and spacing member provided in the construction described in the specification filed with the application of Sven Svensson, Ser. No. 666,639; filed Apr. 18, 1933, and being adapted to be secured in position by means of a milled pinching 90 screw 14.

On the removal of the auxiliary bar 11 the bar 1 with its knife 2 may be employed in the production of ornamental fabrics by the method described in the specification filed with the application of Jean Gregorius Sakellarides, dated 25th February, 1933, Serial No. 658,552. When the auxiliary bar 11 is in position, the mode of operation of the device may be similar to that of the construction described in the specification filed with the application of Daniel H. Chason dated January 4th, 1933, Serial No. 650,073.

Referring to the modified construction shown in Figs. 4—13 the device illustrated consists of a primary bar 15 to which is removably fitted a knife 16 and to the free or distal end of which is pivoted at 17 a spacing clip 18 engageable with the free or distal end of an auxiliary bar 19 adjustable widthwise of the primary bar 15 110

and removable therefrom. The outwardly directed cutting edge 16' of the knife 16 projects beyond and is inclined to the outer edge of the bar 15. Cooperative with the knife 16 is a 5 second knife 20 the inwardly directed cutting edge 20' of which forms in conjunction with the cutting edge 16' of the first knife 16 a shear cutter for the yarn loops, said second knife 20 constituting a guard for the first knife 16. A- 10 fording a backing or support for the second knife 20 is a plate 21 presenting a resilient lug 22 engageable with the underside of the bar 15. The knives 16, 20 and the backing plate 21 are detachably interconnected by screws 23 threaded 15 into the backing plate 21. Depending from the knife 16 towards one end thereof is a pin 24 engageable with an aperture 25 in the bar 15. Upstanding from the lug 22 is a pip 26 engageable with an aperture 27 in the bar 15. The 20 knife 16 is engageable with a seat 28 formed in the upper face of the bar 15 and presenting at one end an undercut ledge 29 affording a groove engageable by a beveled edge 30 on the adjacent end of the knife 16. As will readily be understood, the knife assembly is held in position on 25 its seat 28 by the engagement of the pin 24 with the aperture 25, by the engagement of the pip 26 with the aperture 27, and by the engagement of the beveled edge 30 with the undercut ledge 29. 30 The knife assembly is removable from and remountable upon its seat 28 simply by swinging the knife assembly about the axis of the pin 24 to cause the pip 26 to snap out of engagement with or to snap into engagement with the aperture 27 and to cause the beveled edge 30 to become disengaged from or to engage the groove presented by the undercut ledge 29.

The auxiliary bar 19 has at its proximal end a cranked portion 31 slideable in a transverse 40 guideway 32 presented by a forked member 33 attached to the proximal end of the bar 15 and affording a handle or finger grip 34. A pinching screw 35 is provided for securing the cranked portion 31 of the auxiliary bar 19 in its position of adjustment in the guideway 32.

The spacing clip 18 is of forked form to straddle the distal ends of the bars 15, 19, being formed with registering slots 36 entered by the pivot pin 17 and dimensioned to permit bodily 50 movement of the clip so as to provide for variable spacing of the auxiliary bar 19 from the primary bar 15. Pivoted at 37 to the clip 18 is a latch member 38 presenting interdental notches 39 engageable selectively with the pin 17 to determine the spacing between the distal 55 ends of the bars 15, 19 while permitting free pivotal movement of the clip about the pin 17. A small blade spring 40 located within the auxiliary-bar-engaging socket 41 of the clip 18 is adapted frictionally to engage the distal end of 60 the auxiliary bar 19 so as normally to hold the clip in operative position.

Indicating lines are marked on the cranked portion 31 of the auxiliary bar 19 representing 65 different predetermined adjustments of the auxiliary bar widthwise of the primary bar, such indicating lines being spaced equidistantly with the interdental notches 39 of the latch member 38.

The further modification shown in Figs. 14 and 70 15 comprises a primary bar 42, a knife mounted on said bar 42, a spacing member 44 and an auxiliary bar 45 adjustable widthwise of and detachable from the bar 42.

In this construction, as in the construction 75 illustrated in Figs. 4-13, there is used a double

shear-forming knife comprising an upper knife 46, a cooperative lower knife 47, and a backing plate 48. The knives 46, 47 and the backing plate 48 are secured to one another by screws 49. The knife assembly is detachably secured to the bar 42 in manner similar to the construction described with reference to Figs. 4-13, the knife 46 being provided with a pin 50 engageable with an aperture 51 in the bar 42 and the backing plate 48 being provided with a pip 52 engageable with an aperture 53 in the bar 42. As in the construction illustrated in Figs. 4-13, when it is desired to remove the knife assembly from the bar 42, it suffices to rock the knife assembly about the pivot formed by the pin 50, the pip 52 snapping out of the aperture 53 and the beveled edge of the knife 46 being disengaged from the undercut ledge on the bar 42, whereby the entire knife assembly can be removed from the bar 42. There are then no projecting parts on the bar 42. To attach the knife assembly again, first the pin 50 is inserted into the aperture 51 and the knife assembly is rocked about this pin 50 as a pivot until the pip 52 snaps into the aperture 53 in the bar 42. As the knife assembly embraces the 100 bar 42 in clamp fashion, secure holding of the knives to the bar is ensured.

The auxiliary bar 45 has at its proximal end a bent portion 54 slideable in a guideway 55 presented by a forked member 56 attached to the proximal end of the bar 42 and affording a handle or finger grip 57. As will be understood, throughout its range of adjustment the bar 45 is maintained parallel with the bar 42. A pinching screw 58 threaded into the member 56 is 110 engageable with the bent portion 54 of the bar 45 to lock the bar 45 in its position of adjustment.

To support the distal end of the auxiliary bar 45 there is pivoted at 59 to the distal end of the bar 42 the spacing member 44 which can be 115 swung into alignment with the bar 42 as shown in dotted lines in Fig. 14. Formed in the spacing member 44 is a number of notches 60 engageable by the tapered distal end of the auxiliary bar 45.

In order to facilitate the exact parallel adjustment of the auxiliary bar 45 there is provided on its lower bent end portion 54 a number of marking lines, and correspondingly there is provided on the outer face of the spacing member 44 a number of marking lines corresponding to 125 the several notches 60.

When the spacing member 44 is swung into the position indicated in dotted lines and the knife assembly removed, work can also be done in forming and stitching unsevered loops.

In the further modified construction shown in Figs. 16 and 17 the knife assembly comprises an upper knife 61, a lower knife 62, and a backing plate 63, as in the constructions shown in Figs. 4-15.

The upper knife 61 is connected with the backing plate 63 by means of screws 64, 65. On the knife 61 there is also provided a pin 66 engageable with an aperture 67 in the main bar 68. On the backing plate 63 there is provided a pip 69 engageable with an aperture 70 in the bar 68. The knife assembly is detachable from the bar 68 by rocking the knife assembly about the pin 66, as in the constructions according to Figs. 4-15. The knife 62 which is formed with a recess 71 engageable by the finger nail is formed also with an open ended slot 72 engageable with a pin 73 upstanding from the backing plate 63. Alongside the cutting edge the knife 62 has an arcuate guide slot 74 concentric with the pin 73 and engageable 150

with the shank of the screw 65. When the screw 65, in the position of the parts shown in Fig. 16, is loosened somewhat, the knife 62 may be swung about the pin 73 as a pivot whereby to shift the 5 cutting point in case, for example, the cooperating cutting edges of the knives have become blunt at the cutting point. The knife 62 is secured in its position of adjustment by tightening the screw 65. Also, the knife 62 may be swung 10 about the pin 73 as a pivot until the guide slot 74 comes out of engagement with the shank of the screw 65 whereby the knife 62 can be entirely removed, so that with suitable formation of the 15 knives and backing plate convenient sharpening of the cutting edges of both knives is made possible or the knife 61 alone can be used for cutting the yarn loops.

75 denotes a spacing member for spacing the distal end of the main bar 68 from the distal end 20 of the auxiliary bar 76, said spacing member 75 being mounted for pivotal and bodily movement similar to the spacing member 18 in the construction illustrated in Figs. 4-13.

I claim:—

25. 1. A device of the class described, comprising a forked loop-forming member having two prongs separated by a stitch-receiving gap, and a loop-cutting knife and knife-guard secured to one of said prongs.

30. 2. A device of the class described, comprising a forked loop-forming member having two prongs separated by a stitch-receiving gap, a loop-cutting knife and a knife guard removably fitted to one prong, and a spacing member for spacing the 35 free ends of said prongs.

40. 3. A device of the class described, comprising a forked loop-forming member having two prongs widthwise adjustable relatively to one another to vary the gap between said prongs, a loop-cutting knife removably fitted to one of said prongs, and a spacing member anchored to said last mentioned prong for spacing the free ends of said prongs.

45. 4. A device of the class described, comprising a flat loop-forming bar having parallel edges, a knife adjacent to one end of said bar having a cutting edge extending beyond and inclined to one of said parallel edges, a guard for said knife, a second bar spaced from the other of said parallel edges to afford a stitch-receiving gap between said 50 bars, said second bar having one end removably connected to said first mentioned bar, and means independent of said guard for spacing the free ends of said bars.

55. 5. A device of the class described, comprising a flat-loop-forming bar having parallel edges, a knife adjacent to one end of said bar having a cutting edge extending beyond and inclined to one of said parallel edges, a second bar spaced from the other of said parallel edges, said second 60 bar having one end removably connected to said first mentioned bar and being widthwise adjustable relatively to said first mentioned bar, and means permanently connected to the free end of said first mentioned bar for spacing said bars.

65. 6. A device of the class described, comprising a flat loop-forming member, and a loop-cutter adjacent to one end of said member, said loop-cutter consisting of a pair of knives removably secured to one another and to said loop-forming member.

70. 7. A device as claimed in claim 6 in which one knife is in pin and aperture engagement with the loop-forming member and the other knife has a removable connection with the first knife.

75. 8. A device of the class described, comprising a

pair of separable bars, connectible with one another in parallelism to constitute a forked structure, a loop-cutting knife and knife guard fitted to one of said bars, and a spacing member for spacing the free ends of said bars.

80

9. A device of the class described, comprising a forked loop-forming member having two prongs widthwise adjustable relatively to one another to vary the gap between said prongs, a loop-cutting knife fitted to one of said prongs, and a spacing member connected for pivotal and bodily movement with one of said prongs for spacing the free ends of said prongs.

85

10. A device of the class described, comprising a flat loop-forming bar having parallel edges, a loop-cutting knife adjacent to one end of said bar presenting a cutting edge extending beyond and inclined to one of said parallel edges, a second bar connected at one end to said first mentioned bar and widthwise adjustable in parallelism with the other of said parallel edges, and a spacing member having a pin and slot connection with said first mentioned bar and engageable with the free end of said second mentioned bar.

90

11. A device of the class described, comprising a flat loop-forming bar having parallel edges, a knife adjacent to one end of said bar presenting a cutting edge extending beyond and inclined to one of said parallel edges, a second bar connected at one end to said first mentioned bar so as to be 105 widthwise adjustable relatively to said first mentioned bar, and a spacing member connected to the free end of said first mentioned bar and operative to maintain said second bar spaced from said first mentioned bar in different positions of 110 adjustment of said second bar.

12. A device of the class described, comprising a flat loop-forming member presenting a straight edge, and a knife and a knife-guard fitted to said member adjacent to one end, said knife having a 115 cutting edge extending beyond and inclined to said straight edge, said guard having a cutting edge forming an acute angle with the cutting edge of said knife.

13. A device for the purpose specified, comprising a flat loop-former, and a loop-cutter presenting shear knives removably secured to one another, one of said knives being detachably engageable with said loop-former.

14. A device of the class described, comprising 120 a flat loop-forming bar, a knife fitted to the upper face of said bar and having a cutting edge extending beyond one edge of said bar, a backing member engageable with the under face of said bar, and a second knife interposed between said first 125 mentioned knife and said backing member and having a cutting edge forming an acute angle with the cutting edge of said first mentioned knife.

15. A device of the class described, comprising 130 a flat loop-forming bar, a handle at one end of said bar presenting a guideway disposed transversely of said bar, a second bar in parallelism with said first mentioned bar and having a cranked end adjustable in said guideway, and a 135 knife fitted to said first mentioned bar adjacent to its opposite end.

16. A device of the class described, comprising 140 a loop-forming bar, a second bar parallel to said first mentioned bar and widthwise adjustable 145 relatively to said first mentioned bar, a member for spacing the free ends of said bars, said spacing member having a pin-and-slot connection with said first mentioned bar, and a latch mem-

150

- ber engageable with the pin for locking said bars in their position of relative adjustment.
17. A device of the class described, comprising a loop-forming bar having parallel edges, a knife 5 fitted to said bar and having a cutting edge extending beyond one of said parallel edges, a second bar spaced from the other of said parallel edges to afford a stitch-receiving gap between said bars, said second bar having one end ad-
- 10 justably connected to said first mentioned bar, a clip pivotally connected to said first bar and engageable with the free end of said second bar, said clip shiftable on its pivot to accommodate variation in the spacing of said bars.
- 15 18. A device of the class described comprising a loop-forming bar having parallel edges, a knife fitted to said bar presenting a cutting edge extending beyond and inclined to one of said parallel edges, a second bar spaced from the other of 20 said parallel edges to afford a stitch-receiving gap between said bars, said second bar connected at one end to said first mentioned bar so as to be widthwise adjustable relatively to said first mentioned bar, a pivot pin at one end of said first 25 mentioned bar, a clip having a slot penetrated by said pivot pin, said clip engageable with the free end of said second bar, and a notched latch member pivoted to said clip and engageable with said pivot pin.
- 30 19. A device for the purpose described, comprising a loop-former, and a loop-cutting knife and a knife guard removable as a unit from said loop-former.
20. A device for the purpose specified, comprising 35 a flat loop-forming bar formed with a pair of apertures, a loop-cutter presenting shear knives, one of said knives provided with a pin engageable with one of said apertures, and a backing member for the other knife, said backing 40 member having means engageable with the other of said apertures.
21. A device for the purpose specified, comprising a flat loop-former and a loop-cutter presenting shear knives fitted to said loop-former, said 45 knives being relatively adjustable.
22. A device for the purpose specified, comprising a flat loop-forming bar and a cutter presenting shear knives fitted to said loop-former, one of said knives being angularly adjustable 50 relatively to the other knife and removable therefrom.
23. A device for the purpose specified comprising a loop-former, and a loop-cutting knife removably attached to said loop-former, said knife having a pin and aperture and beveled edge and groove connection with said loop-former. 80
24. A hand tool for the purpose specified, comprising a flat loop-former adapted to be held in the hand of an operator to receive a winding of yarn or the like thereon, and a loop-cutter presenting shear knives fitted to said loop-former. 85
25. A hand tool for the purpose specified, comprising a flat loop-former adapted to be held in the hand of an operator to receive a winding of yarn or the like thereon, and a loop-cutter presenting shear knives removably fitted to said loop-former. 90
26. A hand tool for the purpose specified, comprising a flat loop-former adapted to be held in the hand of an operator to receive a winding of yarn or the like thereon, and a loop-cutter consisting of superposed knives fitted to said loop-former. 95
27. A hand tool of the class described, comprising a flat loop-forming member adapted to be held in the hand of an operator to receive a winding of yarn or the like thereon, a loop-cutting knife having an outwardly directed edge adjacent to one end of said member, and a cooperative loop-cutting knife having an inwardly directed edge and constituting a guard for said first member. 100
28. A hand tool for the purpose specified, comprising a flat loop-former adapted to be held in the hand of an operator to receive a winding of yarn or the like thereon, and a loop-cutter presenting separable shear knives fitted to said former. 110
29. A device of the class described, comprising a forked loop-forming member having two prongs separated by a stitch-receiving gap, a knife on one of said prongs, and a spacing member detachably connecting the free ends of said prongs together beyond said knife. 115
30. A device of the class described, comprising a forked loop-forming member having two prongs separated by a stitch-receiving gap, a knife on one of said prongs having a cutting edge directed away from the other prong, and a spacing member detachably connecting together the free ends of said prongs. 120
